UNITED STATES PATENT OFFICE.

JAMES HUDSON, OF BIRMINGHAM, COUNTY OF WARWICK, ENGLAND.

WHEEL FOR VELOCIPEDES.

SPECIFICATION forming part of Letters Patent No. 339,550, dated April 6, 1886.

Application filed August 21, 1885. Serial No. 174,993. (No model.) Patented in England January 2, 1885, No. 64.

To all whom it may concern:

Be it known that I, JAMES HUDSON, a subject of the Queen of Great Britain, residing at Tennant Street, Birmingham, in the county 5 of Warwick, England, manufacturer, have invented new and useful Improvements in the Construction of Rims or Tires of Wheels for Bicycles, Tricycles, and other Vehicles, (for which I have obtained provisional protection 10 for a patent in Great Britain, No. 64, bearing date January 2, 1885,) of which the following is a specification, reference being had to the accompanying drawings.

Hitherto the rims of wheels similar to those 15 described in the title have been either drawn from weldless tubes or from sheet-steel and soldered on the outside of the tube; but either of these two methods is objectionable—the first on the ground of expense, and the second on 20 the ground of the disfigurement of the outer surface of the tube by the solder upon the joint.

In the tubing for my improved rim I roll or otherwise form the strip of metal of which it 25 is constructed to any desired strength, but thickened in its center. This is for the purpose of giving the desired strength to the under side of the rim, through which holes to receive the spokes are drilled. I then draw the 30 tube of which the rim is afterward formed in the usual manner, and by preference the joint is in the hollow of the rim. It will be understood that by this means I can produce a rim with a clean surface, and the joint being protected under the india-rubber tire, it is not 35 liable to perish. In some cases I employ rolls to form the said tubes, instead of drawing them through dies.

Instead of drawing the tubes of which my 40 improved rim is formed from sheet-steel, I in some cases use steel or iron tubes.

I will now describe, with reference to the accompanying drawings, the manner in which my invention is to be performed.

Similar letters of reference denote the similar parts in each figure in which they occur.

Figure 1 is a section through a tube constructed according to my invention. Fig. 2 is a section through a wheel-tire made of tube 50 constructed according to my invention, showing, also, the india-rubber tire and the attach-

ment of a spoke. Fig. 3 is a partial side elevation of a wheel-tire as above. Fig. 4 is a cross-section of a strip of metal rolled to a suitable section for making a tube according 55 to my invention. Fig. 5 is a cross-section of a circular tube of suitable section for making a tube according to my invention.

A tube made according to my invention is semicircular and concave on the upper side, 60 and nearly semi-elliptical and convex on the under side, as shown in Fig. 1, where A is the metal where of ordinary thickness; B, the thickened part at the bottom for receiving the spokes; C, the joint, and D the brazing, which 65 is placed so as to be hidden by the india-rubber tire E, Fig. 2.

In Fig. 2, A is the ordinary thickness of the metal; B, the thickened part; E, the india-rubber tire, and F the spoke. 70

The same parts and reference-letters occur in Fig. 3.

In Fig. 4, A A show the metal strip where of the ordinary thickness, and B shows the thickened part, which I place, by preference, in the middle. 75

In Fig. 5, which shows a round tube, which is afterward drawn through dies to bring it to the required shape, G shows the metal of ordinary thickness, and H the thicker part. 80 When the tube is drawn to the required section, the part H becomes B, Figs. 1, 2, and 3.

I am aware that tubular wheel-rims have heretofore been made either from previously-prepared tubes or from strips of metal to 85 which the required shape has been imparted.

I am also aware that such rims have been thickened where attached to the spokes. This thickening of the tubular rims has, however, been generally accomplished either by forming 90 the joint of the tube on its under side and lapping or doubling the edges of such joint, or else by forming a butt-joint and soldering or brazing a strip of metal over said joint to cover it. Both these methods, however, differ from my within-described invention, in that I form the joint in the upper concaved side of the rim beneath the rubber tire and diametrically opposite the thickened portion 95 of the tubular rim, such thickened portion being, moreover, integral with the texture of the rim and formed therein while the latter is 100

being rolled or drawn into shape. By forming the thickened under side of the tubular rim in this manner I avoid the difficulty and expense of soldering or brazing a strip to the 5 rim for the purpose of securing the required thickness, as well as the liability of such strip becoming worn or detached.

My construction also affords a more firm and durable support for the spokes than can 10 be secured by making a lap-joint on the under side of the rim and attaching the spokes therein.

Having fully described my invention, what 15 I desire to claim and secure by Letters Patent is—

A tubular wheel-rim provided with a concaved or grooved periphery semicircular in cross-section, with a joint formed therein, and having its underside convex, nearly semi-elliptical in cross-section, and longitudinally thickened at the center, in combination with a rubber tire set in the periphery of said rim, as set forth. 20

JAMES HUDSON.
